UNITED STATES PATENT OFFICE.

REINHOLD BURGER, OF BERLIN, GERMANY.

MAKING DOUBLE-WALLED VACUUM VESSELS.

No. 923,136.

Specification of Letters Patent.

Patented June 1, 1909.

Application filed January 5, 1909. Serial No. 470,863.

To all whom it may concern:

Be it known that I, REINHOLD BURGER, a subject of the German Emperor, residing at Berlin, Germany, have invented a certain 5 new and useful Improvement in Making Double-Walled Vacuum Vessels, of which the following is a specification.

The invention relates to the manufacture of double walled glass vacuum vessels, such 10 as bottles, and consists broadly in the process hereinafter described and comprising the steps more particularly pointed out in the claims.

In the accompanying drawings which are 15 all longitudinal sectional views—Figure 1 shows separately the glass cylinder which ultimately forms the outer wall of the bottle. Fig. 2 shows separately the glass cylinder which ultimately forms the inner wall 20 of the bottle. Fig. 3 shows the cylinder of Fig. 2 placed within the cylinder of Fig. 1, and the supporting bodies in place between the walls. Fig. 4 shows the two cylinders connected only at one end of the neck or 25 mouth of the new double walled vessel. Fig. 5 shows the double walled vessel with the open bottom end of the outer cylinder closed and tubular projections formed thereon. Fig. 6 shows the same with one of 30 said projections sealed, and Fig. 7 the same with both of said projections sealed.

Similar letters of reference indicate like parts.

I carry my process into effect in the following manner: The glass cylinder A, which is to form the outer wall of the vacuum vessel, is preferably made with a contraction or neck B at one end, and is open at both ends, as shown in Fig. 1. The 35 glass cylinder C, which is to form the inner wall of the vacuum vessel, is of less diameter than cylinder A, and is preferably made with an open contraction or neck D at one end and is closed at the opposite end. The cylinder C is placed within the cylinder A, as shown in Fig. 3, and supporting bodies or plugs E, preferably made of asbestos paper or other yielding heat insulating material, are introduced in any suitable way 45 into the space between said cylinders. Said

plugs may be attached to the outer surface of the inner cylinder C in any suitable manner, such for instance, in the way set forth in U. S. Letters Patent No. 888,783, granted to me May 26, 1908, before the said cylinder C is inserted into the cylinder A, or by adhesion; or they may be inserted into the space between said cylinders after said cylinders are put together and then retained in place by engagement with the 55 walls. For convenience in handling and spacing, they may be connected by a ring F of wire or cord.

The two cylinders are next fused together at their mouths, as shown in Fig. 4, and 60 then the open end of the cylinder A is closed and two tubular projections G, H formed thereon, as shown in Fig. 5. In order to fill the pores of the glass, a silvering solution 65 may be introduced into the space between the walls and a coating of silver thus applied. One of the projections, as H, is then sealed, Fig. 6, and substantially a vacuum 70 is produced in the said space by any suitable device applied to the remaining projection 75 G. The last named projection is then sealed, thus completing the vessel, as shown in Fig. 6.

I claim:

1. The process of making glass vacuum 80 vessels which consists in, first, placing within a glass cylinder open at both ends, a second cylinder of less diameter closed at one end, so that a space will be formed between said cylinders and introducing permanent 85 supporting bodies into said space: second, fusing together the contiguous open ends of said cylinders: third, closing the open end of the outer cylinder leaving said supporting body in place: fourth, forming an opening in said closed end: fifth, producing substantially a vacuum in said intermediate 90 space, and sixth, closing said opening.

2. The process of making glass vacuum 95 vessels which consists in, first, placing within a glass cylinder open at both ends, a second cylinder of less diameter closed at one end, so that a space will be formed between said cylinders and introducing permanent supporting bodies into said space: second, 100

fusing together the contiguous open ends of said cylinders: third, closing the open end of the outer cylinder leaving said supporting body in place: fourth, forming on said 5 closed end two tubular projections: fifth, introducing coating solution into said space: sixth, closing one of said tubular projections: seventh, producing substantially a

vacuum in said space, and eighth, closing said remaining tubular projection.

In testimony whereof I have affixed my signature in presence of two witnesses.

REINHOLD BURGER.
